ROTATABLE WORK HOLDER FOR
ELECTROPLATING APPARATUS

Lorren E. Collessier, Chicago, Ill., assignor to
Mercil Plating Equipment Company, Chicago,
Ill., a corporation of Illinois

Application January 17, 1950, Serial No. 139,050

13 Claims. (Cl. 259—89)

1

This invention relates to electroplating apparatus and more particularly to the structure of the plating barrels.

It is an object of the invention to provide an electroplating apparatus of improved construction and improved operating characteristics.

More specifically it is an object of the invention to provide an improved plating barrel construction which plating barrel construction gives increased strength and greater internal volume with the same overall external dimensions used heretofore in the art.

Another object of the invention is to provide an improved plating barrel having a greater area for the transfer of electroplating solution from the inside to the outside of the barrel and vice versa.

A further object of the invention is to provide an improved plating barrel having an increased plating capacity for given overall external dimensions.

Still another object of the invention is to provide a plating barrel having improved means therein for redistributing parts to be plated within the barrel.

A further object of the invention is to provide an electroplating apparatus having a greater plating capacity, an increased operating efficiency and requiring lower maintenance expenses.

Various other objects, advantages and features of the invention will be apparent from the following specification when taken in connection with the accompanying drawings where certain preferred embodiments are set forth for purposes of illustration.

In the drawings wherein like reference numerals refer to like parts throughout:

Figure 1 is a general assembly view, partly in section, of an electroplating apparatus constructed in accordance with and embodying the principles of the present invention;

Figure 2 is an end view of the apparatus shown in Figure 1;

Figure 3 is a partial enlarged view in cross-section of a bearing and electrode structure forming a part of the apparatus of Figures 1 and 2;

Figure 4 is a perspective view of a plating barrel made in accordance with and embodying the principles of the present invention;

Figure 5 is a view in vertical cross-section of the plating barrel shown in Figure 4;

Figure 6 is a cross-sectional view of the plating barrel shown in Figure 5 as seen in the direction of the arrows along the line 6—6 thereof;

Figure 7 is a partial view in cross-section of the

2

barrel shown in Figure 6, illustrating the application of the preferred type of cover clamp;

Figure 8 is a partial view of a plating barrel showing two sides and an end plate thereof in exploded relationship;

Figure 9 is a partial view of a plating barrel showing the manner in which the end plates are secured to the side members;

Figure 10 is an enlarged view of one end of the fastening element shown in Figure 9;

Figure 11 is an enlarged partial view in cross-section showing the joint between two sides of the plating barrel; and,

Figure 12 is an enlarged partial view in vertical cross-section of another improved form of electrode structure.

Referring to the drawings and more particularly to Figures 1 and 2 thereof, there is shown an electroplating apparatus constructed in accordance with and embodying the principles of the present invention. The electroplating apparatus comprises generally a tank 20 adapted to contain a body of electrolyte or plating solution at a suitable level such as indicated at 22. A plating barrel, generally designated by the numeral 24, is rotatably suspended in the body of the electrolyte solution by a pair of hanger arms 26 and 28.

The plating barrel 24 is adapted to contain the articles to be plated, and is rotated by a mechanism to be described hereinafter.

Hanger arms 26 and 28 are suspended from a frame structure which is removably supported on the top of a tank 20 so that the plating barrel with its associated hanger arms and support frame may be removed as a unit from the tank to effect the removal and replacement of the plated articles or articles to be plated from the barrel. The frame structure is supported by brackets 30 and 32 provided on the upper rim of tank 20. These brackets removably receive shafts 34 which form a part of the barrel supporting frame and from which the hanger arms 26 and 28 are suspended. The barrel supporting frame also includes a shaft 36 carrying a hook 38 by means of which the frame hanger arms and barrel may be removed from the tank as a unit by any suitable lifting device.

Mechanism provided for rotating the barrel comprises a gear or pulley 40 adapted to be connected to a suitable source of power. This gear or pulley, as the case may be, is mounted on a stub shaft 42 which is formed as a part of the barrel supporting frame. Shaft 42 also carries a pinion 44 which meshes with a gear 46 suit-

ably secured to a trunnion sleeve journaled within a bearing portion 48 formed on the lower end of hanger arm 26. The trunnion sleeve (not shown) and the gear 46 are both secured to the right end plate 50 of the barrel 24, as will be more particularly described hereinafter, whereby the barrel is rotated in response to the movements of gear 46.

The pump 52 driven by an electric motor 54 is provided and connected to a pipe 56 in such a manner as to circulate the electrolyte from the lower portion of tank 20 through a central opening (not shown) in the bearing portion 48 of the hanger sleeve 26 and into the barrel, whereby to effect electrolyte circulation. These details of construction form no part of the present invention except insofar as they cooperate with the structures hereinafter set forth.

The tank 20 carries a pair of support bars 60 from which a plurality of anode bars 62 can be conveniently suspended. The supports 60, which are grounded to the tank 20, form a part of the electrical circuit for the plating current, as is diagrammatically indicated by the wires 64 in Figure 2. The anode bars cooperate with cathode structures carried by the barrel and against which the articles to be plated within the barrel are adapted to engage, the current passing between the cathode and the anode bars through the electrolyte to effect the plating operation, as is well understood in the art. The cathode structures will be more fully described hereinafter.

The rotatable plating barrel 24 and its associated frame structure and hanger arms are electrically insulated from tank 20, one terminal of the electric circuit being connected to the cathode within the plating barrel through the hanger arm 26, as will be described more fully in conjunction with Figure 3.

Referring to Figure 3, there is shown in cross section a cathode contact made in accordance with and embodying the principles of the present invention. This cathode contact is positioned within the left end of barrel 24, and is mounted upon the left end plate 66 thereof. The cathode contact, generally designated by the numeral 68, is substantially circular in shape and is provided with an aperture in the center thereof. A substantially laterally extending flange 70 is formed on the circumference of the cathode contact to give greater contact area, and another flange 72 is formed about the aperture in the center of cathode contact 68. As will be understood, the cathode contact is made of any suitable conducting material.

A conducting trunnion 74 having a boss which extends through the aperture in cathode contact 68 is provided to support the cathode and to provide a means for applying electrical current thereto. A circular-shaped flange 76 extends laterally from the conducting trunnion 74 and has apertures positioned therein to receive a plurality of screws 78 that fasten the conducting trunnion 74 to a fill-in flange 80 which is made of a suitable non-conducting material such as a plastic. The cathode contact 68 is held in position upon the conducting trunnion 74 and the fill-in flange 80 by means of a bolt 82, which is threadedly received in an aperture in trunnion 74. A plurality of insulating washers 84, 86 and 88 are provided to protect metal parts which are not intended to form part of the cathode contact area from the plating solution. More particularly, washer 88 protects the laterally extending

flange 76 of trunnion 74 and the screws 78. Washers 84 and 86 protect the threaded portion of screw 82 and the portion of the trunnion 74 which extends through the aperture in cathode 68. By protecting these exposed metal parts from the electrolyte solution, treeing is prevented or reduced to a minimum. The prevention of treeing greatly facilitates removal, replacement and repair of various cathode parts. It will be seen that bolt 82 secures washers 84, 86 and 88 and the cathode contact 68 in proper relation upon the proper associated parts.

An aperture is formed in end plate 66 to receive a supporting bearing member, and there is also attached to end plate 66 an apertured flange 90 which gives added supporting bearing area. A plurality of bolts 92 holds the flange 90 and the end plate 66 in proper relationship so that the apertures therein coincide, and the same bolts 92 attach the fill-in flange 80 and its associated parts to the end plate 66. The heads of bolts 92 are countersunk, and plugs 94 of insulating material are provided to protect the heads of the bolts from the electrolyte solution whereby to prevent treeing thereon. It will be seen from the above description that end plate 66 and flanges 80 and 90 and associated parts will rotate together as a unit when gear 46 is rotated.

The rotatable mounting for the left end of barrel 24 comprises a bearing portion 96 formed on the end of hanger arm 26, a hanger arm trunnion 98 and a bushing 100 which cooperate with the supporting bearing apertures in plate 66 and flange 90 which were described above. All of these parts are made of insulating or non-conducting material such as a plastic. The hanger arm trunnion 98 is substantially circular in cross section, having a flange 102 formed at one end thereof, and fits within a complementarily-shaped aperture in bearing portion 96 with one end thereof extending into the bearing apertures of flange 90 and end plate 66. The bushing member 100 is cylindrical in shape and has an aperture formed in the center thereof whereby to allow the bushing to be positioned over the outwardly extending end of the hanger arm trunnion 98. The surface between the bushing 100 and the edges of the apertures in end plate 66 and flange 90 form the bearing surface. The hanger arm 26, the hanger arm trunnion 98 and the bushing 100 form the stationary portion of the bearing, with the barrel end 66 and associated parts revolving thereon. A washer 104 is positioned between the end of the hanger arm trunnion 98 and the fill-in flange 80 to provide a bearing surface therebetween, especially in the event that side thrust is encountered.

Electrical current is supplied to the cathode contact 68 through an electrical conductor 106 which is preferably provided with an impermeable insulation such as a rubber cover. The conductor 106 is mounted on the hanger arm 26 and connects with an insulated electrical circuit mounted within the bearing described above. Conductor 106 passes through coinciding apertures in the bearing portion 96 of hanger arm 26 to an axially extending aperture formed in trunnion 98. An insulating tube 108 lines the aperture in trunnion 98 and an insulator bushing 110 protects the portion of conductor 106 which is positioned within the aperture of trunnion 108. Electrical connection between conductor 106 and the conducting trunnion 74 is

provided by a metallic conducting shaft 112 positioned within insulator tube 108. It will be seen that a complete insulated current path is provided from the source of current through conductor 106, shaft 112, and conducting trunnion 74 to the cathode contact 68. The conducting shaft 112 is held stationary with respect to the hanger arm 26, while the conducting trunnion 74 rotates with the plating barrel. It will thus be seen that a sliding electrical contact is made between the conducting shaft 112 and the conducting trunnion 74.

The cathode contact structure shown in Figure 3 provides an increased electrode area as compared with electrode structures known heretofore in the art and thus gives more rapid plating and increases the capacity of the plating barrel. It will be seen from Figures 1 and 3 that the entire contacting area of cathode contact 68 is immersed in the electrolyte solution at all times and is never removed therefrom while the barrel is in operation. Positioning the electrode structure on the end plate in the particular structure shown facilitates assembling and disassembling of the structure for cleaning and repairing. In particular, the cathode contact 68, which is most subject to wear and treeling, can be removed and replaced by merely unscrewing bolt 82. It further has been found that with cathode structures of the type described the amount of repair and cleaning necessary is materially reduced since all extraneous metal parts are very effectively protected from the electrolyte solution and hence there is no tendency to tree.

Figure 4 is a perspective view of a plating barrel embodying another important feature of the present invention. More specifically, the plating barrel shown in Figure 4 embodies a new manner of joining the sides of the plating barrel whereby to give increased strength in operation and increased capacity and plating rates. The end plates 50 and 66 are substantially hexagonal in shape and hold in assembled position the six sides of the plating barrel to form a cylinder of hexagonal cross section. Referring to Figure 6, it will be seen that sides 114, 116 and 118 are identical with the exception of one structural feature and sides 120 and 122 are also identical except for the same structural feature. Side 114 will be described in detail and the differences of sides 116 and 118 therefrom will be pointed out.

Referring to Figures 5, 6 and 8, panel section 114 comprises generally a rectangularly-shaped frame including a pair of longitudinally extending side members 124-126 interconnected by end members 128-130 and an intermediate bracing member 132. The two rectangular sections thus formed are filled by foraminous sheets 134 and 136. These foraminous sheets are relatively thin compared to the thickness of the frame members, and as may be best seen in Figure 6, are positioned approximately intermediate the depth of the frame whereby to afford maximum strength and yet provide a maximum internal volume for the assembled barrel. The frame and the foraminous sheets preferably are formed as an integral member, such as by molding or casting from a suitable non-conducting material such as a plastic. The longitudinally extending edges of the frame members 124 and 126 are beveled to the proper degree so that the panel sections will fit together.

Means is provided for adjoining adjacent panel

sections in the form of a plurality of double dove-tailed key members 138 which cooperate with suitably formed slots in the edges of the panel sections. The key member 138 is an elongated rod whose cross section as seen in Figure 6 is that of two dove-tailed sections joined along the narrow, parallel sides. The longitudinally extending beveled edges of the panel sections are provided with dove-tailed shaped slots extending the length thereof of a size suitable to receive one-half of the key member 138. When two panel sections are juxtaposed and the key member 138 inserted, it will be seen that the panel sections will be firmly united and will be self-supporting whereby to retain their structural shape. Both of the longitudinally extending, beveled edges of panel sections 114, 116 and 118 are provided with the above described dove-tailed grooves.

20 Panel sections 120 and 122 are similar in construction to panel section 114 and differ therefrom in that only one of the longitudinally extending edges of the frame is provided with a dove-tailed shaped groove.

25 The end plates 50 and 66 are held in position upon the ends of the assembled panel sections by means of a plurality of tie rods 140 which are positioned in apertures formed in the longitudinally extending edges of the frames of the panel sections. These tie rods 140 extend the length of the panel sections and through both end plates. There is a tie rod positioned in each longitudinally extending side frame member of panel sections 114, 116, 118, 120 and 122.

30 35 Both ends of the tie rods 140 are threaded to receive nuts 142 which are recessed in the end plates 50 and 66. The exposed end of the metallic tie rod 140 and the metallic nut 142 are covered by an insulating disk 144 which is held in position and sealed by a quantity of cement 146. Each end of all the tie rods is constructed in this manner.

40 The integral construction of the side panels and the positive interlocking of the adjacent edges of the panel gives a plating barrel whose internal volume is greater for the same over-all external dimensions as compared with plating barrels used heretofore. The increased strength of the plating barrel panel sections allows a greater area of perforations therein, thus allowing for a greater flow of plating electrolyte through the barrel, giving a higher plating rate and greater plating capacity. The greater strength of the barrel, especially the additional strength at the interlocking adjacent edges allows heavier loading during operation as compared with plating barrels known heretofore. The permitted heavier loading in conjunction with the increased volume of the barrel and the increased area of perforation gives a substantial increase in plating capacity, approaching an increase of 50 per cent.

45 50 55 60 65 70 75 A cover 154 is provided to close the opening remaining when panel sections 114, 116, 118, 120 and 122 are assembled with ends 50 and 66. This cover is of substantially the same size as the panel sections, having two longitudinally extending side frame members 156-158, two end frame members 160-162 and two reinforcing members 164-166. The rectangular sections so formed are filled with foraminous sheets 168, 170 and 172 in the same manner as described above with respect to panel section 114. The frame members and foraminous sections preferably are made as one piece by molding or casting from a suitable

non-conducting material such as a plastic. The longitudinally extending edges 156 and 158 of cover 154 are beveled to the appropriate angle to fit with the beveled edges of panel sections 120 and 122.

As may be best seen in Figure 5, gear 46 is connected to end plate 50 by means of a plurality of bolts 148 which connect with end plate 50 through a series of spacers 150. The heads of bolts 148 are countersunk into the gear 46, and the exposed metallic surface is covered by a plastic insert 152.

There is shown in Figures 1, 4 and 7 a preferred type of clamp for securing the cover 154 in position upon the plating barrel 24. This clamp, generally designated by the numeral 174, is generally C-shaped and comprises a central body member 176, a hook member 178 formed on one end of the body member 176, and a screw receiving portion 180. As may be best seen in Figure 7, the central body portion 176 is adapted to overlie the top of cover 154 and the hook member 178 engages an inwardly facing edge of the frame member of panel section 122 when the clamp is in clamping position. The screw receiving member 180 is provided near its end with a threaded aperture to receive the threaded shank 182 of clamping screw 184. The end of shank 182 bears against an inwardly facing edge of the frame member of panel section 122 when the clamp is in clamping position. When the screw 184 is tightened with the clamp in position, as shown in Figure 7, the cover 154 is held tightly in position. The threads on member 180 and on shank 182 are relatively coarse and heavy to give the necessary strength. The clamp 174 and the screw 184 are both made of a non-conducting material such as a plastic whereby to eliminate treeing. As is illustrated in Figures 1 and 4, preferably at least two clamps are used to properly hold the cover in position during operating of the plating barrel. This particular type of clamp is self-adjusting, since as the parts wear the screw 184 need only be screwed in a greater amount to achieve the desired clamping action, and the clamp in addition is simple, easily manipulated and economical in construction.

Another important feature of the present invention is best illustrated in Figures 5, 6 and 11, and comprises a series of tumbling projections 186, which mix and continuously redistribute the parts being plated as the plating barrel 24 is rotated. Projections 186 are substantially triangular in cross section, as may be seen in Figure 6, and are relatively short as compared to the length of a side of the plating barrel. As shown in Figure 5, a number of tumbling projections 186 are positioned along each edge of the hexagonal plating barrel, a preferred arrangement being three equally spaced tumbling projections at one corner, two equally spaced projections on the next corner, three equally spaced projections on the next corner, etc., around the circumference of the barrel. With such an arrangement, tumbling projections on alternate corners of the barrel are staggered whereby to give a greater distributing and mixing effect. These tumbling projections are preferably formed integral with the panel sections and cover. It is to be understood that the shape, number and arrangement of the tumbling projections may be varied and the particular construction in the drawing has been shown merely for purposes of illustration. The continuous redistribution obtained by the use of tumbling projections 186 gives a more uniform plating

for each piece and allows the use of a shorter plating period to give the necessary minimum required plating to each piece. It will be seen, therefore, that the use of the tumbling projections and the increased rate of flow of electrolyte through the plating barrel which is obtained with the improved panel section construction will give a materially decreased plating period required to give the minimum plating to each work piece.

Figure 12 shows another form of an electrode structure which gives a high cathode contact area and which is particularly useful in the plating of small, relatively light work pieces. The bearing structure associated with this electrode structure is similar to the bearing structure described above, which is similar to the electrode structure shown in Figure 3. This bearing structure comprises a bearing portion 96a formed at the lower end of the hanger arm 26a and a hanger arm trunnion 98a, which are mounted in the end plate 66a and its associated insulator washers 90a and 80a. A bearing bushing 100a is interposed between the stationary trunnion 98a and the revolving parts 66a, 80a and 90a to provide a suitable bearing surface. The washers 80a and 90a are held in position on the end plate 66a by a plurality of bolts 92a. The heads of the bolts are countersunk into the flange 90a and are protected from the plating solution by non-conducting plugs 94a.

The plating current for the electrode structure is conducted thereto through an insulated conductor 106a, which connects with conducting shaft 112a that connects with the cathode. A portion of the conductor 106a and all of the conductor shaft 112a are positioned within the trunnion 98a and are surrounded and protected by an insulator tube 108a. A bushing 110a provides support for the conductor 106a near the point of connection between conductor 106a and the conductor bar 112a. The trunnion 98a, insulator tube 108a and the conductor shaft 112a are elongated as compared with the corresponding structure in Figure 3 and extend into the barrel a distance away from the end plate 66a.

The end of trunnion 98a which extends into the plating barrel is countersunk to receive the cathode assembly. The cathode plate 186 is in the form of a circular disk having an aperture in the center thereof, and is connected to the conductor shaft 112a by a cathode connector 188. The cathode connector 188 is generally cylindrical in shape to fit the aperture in the center of cathode plate 186 and has formed on one end thereof a threaded member 190 which is adapted to be screwed into a threaded aperture formed at the end of conductor shaft 112a. To insure a tight fit between the connector shaft 112a and the cathode connector 188, a washer 192 is provided therebetween. The cathode contact plate 186 is only loosely attached to the connector 188, and is held thereon by a non-conducting cap 194 cooperating with a plurality of insulating washers and held in position with a screw 196 which passes through an aperture in cap 194 and threadedly connects with the cathode connector 188. One pair of washers 198-200 encircles the cathode connector 188 and is positioned on either side of the cathode plate 186 which extends substantially perpendicularly with respect to the axis of connector 188. A second pair of washers 202-204 encircle the first set of washers 198 and 200 and are also positioned one on either side of the cathode plate 186.

Support for the cathode plate 186 is provided by two disk-like washers 206-208, which support the cathode plate 186 on both sides thereof. All of the washers 198-200, 202-204 and 206-208 and the cathode plate 186 are held in position by the cap 194 and bolt 196 described above. This arrangement of the cap and washers insures that only the outer portions of the cathode plate 186 come into contact with the plating solution and thus prevent treeing around the points of interconnection between the various metallic parts. With such a manner of assembly, the cathode structure is easily disassembled for repair and replacement.

The path for current from the conductor 186a to the cathode plate 186 is through the conductor bar 112a and the cathode connector 188. It is contemplated that an electrode structure will be positioned at both ends of the plating barrel. Each electrode structure is preferably positioned from the nearest end plate approximately one-third of the length of the plating barrel. In this electrode structure the cathode plate 186 is completely immersed in the electrolyte solution during all the time that the plating barrel is in operation. This cathode structure provides a high plating area and makes possible the use of a simpler bearing support structure.

There has been provided a plating barrel construction and electrode structure which fulfills all of the above objects. More particularly, the barrel structure gives a barrel having the increased strength and greater internal volume for the same over-all external dimensions as compared with plating barrels used heretofore in the art. The greater strength of the plating barrel allows a heavier loading and also permits the use of a larger area of perforations in the panel sections. The combination of the heavier loading, the greater internal volume and the greater area for circulation of electrolyte solution gives approximately a 50 per cent increase in plating capacity per barrel. The improved electrode structure is easier to assemble and disassemble, and provides a greater contact area, which in turn produces a higher plating rate. The provision of tumbling projections gives improved distribution of the parts being plated during the plating operation and gives a more uniform plating to each work piece in a shorter plating period.

It is obvious that various changes may be made in the specific embodiments set forth for purposes of illustration without departing from the spirit of the invention. The invention is accordingly not to be limited to the specific embodiments shown and described but only as indicated in the following claims.

The invention is hereby claimed as follows:

1. A plating barrel for use in electrolytically plating articles comprising a plurality of panel sections, the longitudinally extending adjacent edges of said panel sections being adapted to fit with one another whereby to form a cylindrical barrel, certain of said adjacent edges having a greater thickness than mid portions of the panel sections and having keying grooves formed therein, and keying members positioned within the keying grooves in adjacent panel edges to hold said panel edges in juxtaposed assembled position.

2. A plating barrel for use in electrolytically plating articles comprising a plurality of one-piece panel sections, the longitudinally extending adjacent edges of said panel sections having a

greater thickness than mid portions of the panel sections and being adapted to fit with one another whereby to form a cylindrical barrel, certain of said adjacent edges having keying grooves formed therein, and keying members shaped to fit within the keying grooves in adjacent panel edges whereby to hold said panel edges in juxtaposed assembled position.

3. A plating barrel for use in electrolytically plating articles comprising a plurality of plastic panel sections, the longitudinally extending adjacent edges of said panel sections having a greater thickness than mid portions of said panel sections and being adapted to fit with one another whereby to form a cylindrical barrel, certain of said adjacent edges having keying grooves formed therein, and keying members shaped to fit within the keying grooves in adjacent panel edges whereby to hold said panel edges in juxtaposed assembled position.

4. A plating barrel for use in electrolytically plating articles comprising a plurality of one-piece plastic panel sections, the longitudinally extending adjacent edges of said panel sections having a greater thickness than mid portions of said panel sections and being adapted to fit with one another whereby to form a cylindrical barrel, certain of said adjacent edges having keying grooves formed therein, and keying members shaped to fit within the keying grooves in adjacent panel edges whereby to hold said panel edges in juxtaposed assembled position.

5. A panel section for plating barrels used in electrolytically plating articles comprising relatively thick plastic frame members extending longitudinally of the panel section, and relatively thin plastic foraminous sheet material joining said frame members, said frame members and foraminous sheet being formed integral.

6. A panel section for plating barrels used in electrolytically plating articles comprising relatively thick frame members adapted to lie substantially parallel with respect to the axis of the plating barrel, and relatively thin foraminous sheet means connecting said frame members and filling the space therebetween, at least one of said frame members having a keying groove formed along the longitudinally extending edge thereof.

7. A panel section for plating barrels used in electrolytically plating articles comprising a substantially rectangular relatively thick plastic frame member and a relatively thin plastic foraminous sheet covering the area defined by said frame member and connected to said frame member outwardly of inner surfaces of said frame member, said frame member and said foraminous sheet being formed integral.

8. A panel section for plating barrels used in electrolytically plating articles comprising a substantially rectangular relatively thick frame member, and a relatively thin foraminous sheet covering the area defined by said frame member and connected to said frame member, said frame member having an interlocking keying groove formed along at least one of the longitudinally extending edges thereof.

9. A panel section for a rotatable plating barrel used in electrolytically plating articles comprising a substantially rectangular relatively thick frame member, a relatively thin foraminous sheet disposed within said frame member and filling the area defined thereby, and work tumbling means formed on said frame member

and adapted to protrude into a plating barrel when said panel section is assembled with other panel sections to form a complete plating barrel, said frame member and foraminous sheet and work tumbling means being formed integral.

10. A plating barrel for use in electrolytically plating articles comprising a rotatable multi-sided cylindrical barrel having a plurality of corners, relatively short tumbling projections disposed in the corners of said barrel and projecting inwardly toward the longitudinal axis thereof, the tumbling projections in alternate corners of the barrel being disposed toward the ends of the barrel and the projections on the other corners being disposed toward the center of the barrel to provide a staggered arrangement of the tumbling projections.

11. A plating barrel for use in electrolytically plating articles comprising a rotatable multi-sided cylindrical barrel having a plurality of corners, relatively short tumbling projections disposed in the corners of said barrel and projecting inwardly toward the longitudinal axis thereof, alternate corners of said barrel having three spaced tumbling projections disposed therein, one of said projections being centrally positioned along the longitudinal axis of the barrel and the other two projections being disposed toward the ends of the barrel, the other corners of said barrel having two tumbling projections thereon, the last mentioned tumbling projections being positioned longitudinally of the barrel at places intermediate the first mentioned tumbling projections.

12. A panel section for plating barrels used

5
10
15
20
25

in electrolytically plating articles comprising a substantially rectangular frame member, and a foraminous sheet covering the area defined by said frame member and integrally connected to said frame member, said frame member having a dovetail shaped keying groove formed along at least one of the longitudinally extending edges thereof.

13. A plating barrel for use in electrolytically plating articles, comprising a plurality of panel sections disposed to provide a multi-sided barrel, the adjacent marginal edges of said panel sections having a greater thickness than mid portions of said panel sections, said mid portions having inner surfaces spaced radially outwardly of inner surfaces of said marginal edges, said adjacent marginal edges having keying grooves therein, and keying means disposed in said grooves to hold said panel section edges in juxtaposed assembled position.

LORREN E. COLCLESSER.
